UNITED STATES PATENT OFFICE.

JOSEPH PHILANDER HASTY, OF ENTERPRISE, KANSAS.

SWITCH.

1,282,078.

Specification of Letters Patent. Patented Oct. 22, 1918.

Application filed July 5, 1918. Serial No. 243,423.

To all whom it may concern:

Be it known that I, JOSEPH P. HASTY, a citizen of the United States, residing at Enterprise, in the county of Dickinson and State of Kansas, have invented a new and useful Switch, of which the following is a specification.

The subject of this invention is a switch intended for use on railways.

10 The main object of the invention is the provision of means in the switch throw or stand to prevent injury to the mechanism due to shock or strain.

Another object of the invention is the provision of a lever for a switch throw.

The invention also contemplates generally improving the construction and enhancing the utility of switches.

With the foregoing and other objects in view which will appear as the description proceeds, the invention resides in the combination and arrangement of parts and in the details of construction hereinafter described and claimed, it being understood that 25 changes in the precise embodiment of the invention herein disclosed can be made within the scope of what is claimed without departing from the spirit of the invention.

A practical embodiment of the invention 30 is shown in the accompanying drawing, wherein:—

Figure 1 is a view in elevation of a switch stand constructed in accordance with the invention, a portion being broken away;

35 Fig. 2 is a sectional view taken on the line 2—2 of Fig. 1;

Fig. 3 is a detail view in elevation of the lever;

40 Fig. 4 is a view partly in side elevation and partly in section of the same.

Referring to the drawing by numerals of reference:—

As the invention is an improvement in the switch stand shown and described in my 45 Patent No. 1,258,678, issued March 12, 1918, the general construction of the stand will be but briefly described.

The numeral 1 designates the upright body or stand proper, which is constructed 50 of suitable metal, and which has a suitable base 2 adapted to be secured upon the ties or other foundation, said body 1 being provided with a chamber or cavity 3 in the lower portion thereof opening downwardly 55 to house some of the working parts and protect them from the elements. The upper end

of the body 1 is provided with an annular outstanding flange 4, and a vertical shaft or staff 5 is journaled for rotation through the upper portion of the body 1 and projects 60 downwardly within the chamber 3. The upper end of the shaft 5 carries a suitable signal 6.

As a means for transmitting motion from the actuating shaft 5, a cylindrical cam 7 is 65 secured upon the lower portion of said shaft within the chamber 3, and is provided with a circumferential cam groove 8, provided with a portion 9 extending through substantially one half of a circle and disposed in a 70 common plane at right angles with the shaft 5, said groove 8 having an offset portion 10 also extending through substantially one half of a circle. The lower end of the shaft 5 is journaled or swiveled through a strip or 75 bar 11 terminally secured to the base 2 and extending across the mouth of the chamber 3. The strip 11 is provided adjacent to its opposite edges with upstanding bearings 12 to which are pivoted the elbows of bell crank 80 levers 13.

The bell crank lever 13 constitutes the improvement of the present invention and comprises an arm 30 which merges into the angularly disposed, bifurcated arm 32, between 85 the prongs of which is mounted a strip or bar 33 which projects beyond the ends of the prongs of the arm 32 and forms a section of the other arm of the bell crank lever. The bifurcated arm 32 and the strip 33 are 90 provided with alining apertures, one for the reception of a pin 34 by which the bell crank lever is pivotally connected at its elbow to the supports 12, and the other for the reception of a shear bolt or pin 35. 95

The pin or bolt 35 is made of light material so that the bolt will shear through in case of excessive strain and so relieve the parts of the device from injury.

The arm 30 has a roller 31 pivotally secured thereto which roller fits in the cam groove that the lever may be rocked by the cam.

Links or bridle rods 14 connect the end of the strip 33 with the switch points (not 105 shown) and the device is operated to throw the switch by means of the lever 22, as set forth in the Letters Patent above referred to.

Having thus described the invention, what is claimed as new and sought by Letters Patent, is:—

1. A switch embodying a switch stand, a

bell crank lever fulcrumed in the stand, means engaging one arm of the lever for rocking the lever, a bridle rod connecting the other arm of the lever to a switch point, 5 and a connection between the arms of the lever detachable under excess strain to permit the arms to move independent of each other.

2. A switch embodying a switch stand, a 10 lever fulcrumed in the stand, means engaging one arm of the lever for rocking the lever, a connection between the other arm of the lever and a switch point, and a shear pin connecting the arms of the lever.
- 15 3. A switch embodying a switch stand, a lever fulcrumed in the stand and having one arm bifurcated, a strip inserted in the bifurcated arm and extending beyond the end thereof, a shear pin connecting the strip and 20 the bifurcated arm, means journaled in the stand for rocking the lever, and a bridle rod

connecting the free end of the strip with a switch point.

4. A bell crank lever having a bifurcated arm and an aperture at its elbow and in its 25 bifurcated arm, a strip inserted in the bifurcated arm and extending beyond the end of the arm, said strip having apertures alining with the aperture at the elbow and in the bifurcated arm, a pin inserted through 30 the aperture at the elbow and the alining aperture of the strip, and a shear pin inserted in the aperture in the bifurcated arm and the alining aperture of the strip.

In testimony that I claim the foregoing as 35 my own, I have hereto affixed my signature in the presence of two witnesses.

JOSEPH PHILANDER HASTY.
